Primary Examiner — Darlington Ly*Assistant Examiner* — Jeremy Koenig(74) *Attorney, Agent, or Firm* — CHRISTENSEN O'CONNOR JOHNSON KINDNESS PLLC(57) **CLAIM**

The ornamental design for a wheel rim as shown and described.

DESCRIPTION

FIG. 1 is a front-right-top perspective view of a wheel rim according to aspects of my new design;

FIG. 2 is a front-left-bottom perspective view thereof;

FIG. 3 is a front elevational view thereof;

FIG. 4 is a right-side elevational view thereof, wherein the claimed portions of the left-side elevational view, top plan view, and the bottom plan view are the same as the claimed portion of the right-side elevational view; and,

FIG. 5 is a rear elevational view thereof.

The broken lines in the figures depict portions of the wheel rim that form no part of the claimed design.
